EDWIN W. PUTNAM, OF HARTFORD, CONNECTICUT.

ELECTRICALLY-HEATED FUSING IMPLEMENT.

1,415,479.

Specification of Letters Patent.

Patented May 9, 1922.

Application filed October 28, 1921. Serial No. 511,028.

To all whom it may concern:

Be it known that EDWIN W. PUTNAM, a citizen of the United States, residing at Hartford, in the county of Hartford and 5 State of Conn., has invented certain new and useful Improvements in Electrically-Heated Fusing Implements, of which the following is a specification.

This invention relates to an electrically-heated fusing-implement. An article involving the invention may be utilized with advantage in many different connections, although it is of especial advantage for melting a wafer or body of sealing wax, 15 such as is employed for sealing envelopes and their equivalents, against accidental opening. Among the objects of the invention are the provision of a device of the kind set forth of a simple character by 20 which the requisite amount of heat may be quickly created to fuse a wafer or body of sealing wax.

In the drawings accompanying and forming part of the present specification, I have 25 shown in detail one of the several forms of embodiment of the invention which to enable those skilled in the art to practice the same will be set forth fully in said description. Obviously I am not restricted to such 30 disclosure. I may depart therefrom in several respects within the scope of the invention defined by the claims following said description.

Referring to said drawings.

35 Figure 1 is a side elevation of the implement.

Fig. 2 is a top plan view of the same.

Fig. 3 is a longitudinal section of the head portion of the implement.

40 Fig. 4 is a perspective view of the implement on a smaller scale than the other views, showing a manner of using it.

Like characters refer to like parts throughout the several views.

45 The device as shown comprises in its structure a head 2, which may be in the form of a practically semi-spherical, hollow sheet metal shell having on the lower edge thereof several pendant legs or props 3, which diverge downwardly and which are adapted to rest on a suitable support or foundation to slightly space the heating element, hereinafter described from the surface on which the legs or props 3 rest. The 50 head or shell in addition to the legs or props, is shown provided with a rearwardly

extending tubular neck 4 which constitutes a proper duct for conductors, hereinafter described.

As the implement is desirably manually governed, I prefer to furnish it with a suitable handle as 5 which may be of wood or other proper material, and which is usually hollow to provide for the passage of leads or wires 6 and 7. The handle is desirably, 60 flexibly associated with the head 2 in some manner and the coupling as 8 may be provided for this purpose said coupling as represented, being in the form of a coil of somewhat heavy wire, the terminal portions 65 of which are fitted around the reduced forward end 8' of the handle 5 and the reduced rear portion 9 of the neck 4, it being understood of course that the extreme ends of the coupling 8 are rigidly connected with 70 the handle 5 and head 2 respectively.

The implement involves in its make up a heating element such as that denoted by 10, this heating element as shown being in the 75 form of a whorl of coiled wire. The helices 80 of the coil are laid in a spiral channel 11 formed in the frusto-conical body 12 which with its top annular flange 13 is of some insulating material. This flange 13 as shown, fits within the lower portion of the head or 85 shell 2 and it carries on its upper side terminals as 14 and 15 electrically connected as by wires 16 and 17 with the ends of the heating element 10. The body 12 with its 90 flange 13 and the terminals 14 and 15 together with the connecting wires or conductors 16 and 17, constitute what might be considered as a thermostatic unit.

The head or shell 2 also incloses a terminal member such as that denoted in a general 95 way by 18 and which is generally made of some insulating material. It comprises as illustrated a disk fastened as by screws 19 to the opposite flanges 20 within the head or shell 2. The terminal member 18 has on 100 the under side thereof the plates 21 and 22 fastened in place as by the posts or screws 23 extending through the same and also extending through the disk or terminal member 18 and the enlargement 24 on the upper 105 side of the terminal member or disk 18. The wires 6 and 7 to which I have hereinbefore referred and which extend through the head or shell 2 by way of the neck 4, are 110 connected electrically at their forward ends, which are skinned for the purpose, with the screws or posts 23 and are held thereto

as by nuts 25. The conductors or wires 6 and 7 are intersected by a switch such as that denoted in a general way by 26. When the switch is in "on" current will flow to the 5 plates 21 and 22 through the wires 6 and 7 and will transverse the heating element 10 if the latter be in the correct relation hereinafter described. Obviously when the switch 26 is in the "off" relation no current 10 will be supplied to the heating element. When the parts are in assembled relation the terminals 14 and 15 are projected through openings in the plates 21 and 22 respectively and if the nuts 27 threaded on the base portions 15 of said terminal members 14 and 15, respectively, be in contact with the respective plates 21 and 22, current will flow to the heating element 10 provided the switch 26 be in the "on" relation.

20 In connection with the heating element is a shield 28 comprising as shown, an upper practically cylindrical portion 29 and a lower frusto-conical portion 30. The upper cylindrical portion 29 as shown has in it an annular groove 31 to receive the annular head 13 when the parts are in assembled relation. The shield 28 is spaced somewhat from the heating element 10 and its cylindrical portion 29 has through it perforations or holes 32 for the escape of radiant heat generated by the heating element. Said cylindrical portion 29 has exteriorly thereof the wedge or cam surface 33 engageable by the inner ends of the screws 34 tapped through the 35 legs 3. When these screws 34 are run inwardly they act against the cam surface 33 so as to project the shield 28 upwardly, to thus cause the nuts 25 on the terminals 14 and 15 respectively to engage firmly against the plates 21 and 22 so that if at this time 40 the switch 26 be in the "on" relation the current will be caused to traverse the heating element 10.

The head or shell 2, as shown is provided 45 with a hook 36 by which the implement can be readily suspended from a suitable projection. In addition to this said head or shell has a vent or opening 37 in its top.

While the implement may be used in a 50 variety of ways in different fields, I have however shown in Figure 4 one of the ways it is employed in connection with the sealing of an envelope. In this event the following procedure may be adopted:

55 A wax wafer as 38 will be laid upon the sealed flap of the envelope 39 following which the legs 3 will be laid on top of the flap with the wafer practically centrally of the several legs 3. The contacts 27, in the 60 form of nuts, will then be adjusted firmly against the plates 21 and 22 by the elevation of the shield 28, after which the switch 26 will be moved to the "on" relation to thus cause current to traverse the heating element 65 10. This will heat the heating element and

the radiant heat projected through the central lower opening of the shell, will naturally melt the wafer 38 to which a seal can be subsequently applied.

It will be clear from the foregoing description in connection with the annexed drawing, that the implement comprises in its make up an electric heating element such as the heating element 10, and a guard device surrounding the heating element, the shield 28 answering in this connection. This shield or guard device has means for spacing the heating element from the article to be heated, the spacing means being formed as shown by the legs 3. 70 75 80

What I claim is:—

1. An implement of the class described, comprising a heating element, and a guard device surrounding the heating element and having an opening for radiant heat, the implement being provided with means for positively holding the heating element out of contact with a body in connection with which said implement is being used. 85

2. An implement of the class described 90 comprising a heating element adapted when energized to heat by radiation, a mass of sealing wax on a body, and a guard device surrounding the heating element and having an opening for radiant heat to be projected 95 on to the sealing wax, the implement being provided with means for positively holding the heating element out of contact with said body.

3. An implement of the class described 100 comprising a heating element adapted when energized to heat by radiation a mass of sealing wax on a body, and a guard device surrounding the heating element and having an opening for radiant heat to be projected on 105 to the sealing wax, the implement being provided with legs to support the implement and to also hold the heating element out of contact with said body.

4. An implement of the class described 110 comprising a head, a guard device connected with said head, a heating element in the guard device, a terminal member in the head, provided with contacts, the heating element having contacts to detachably engage those 115 on the terminal member.

5. An implement of the class described comprising a head, a guard device associated with said head, a frusto-conical insulating member in the guard device and the body of 120 which is separated therefrom, a whorl of coiled conducting material fitted around the the body, and a terminal member in the head provided with means for the electrical connection with the whorl, the implement 125 having means to positively hold the heating element out of contact with the part on which said implement rests.

6. An implement of the class described comprising a hollow head, a terminal mem- 130

ber rigidly mounted in the head and provided with contacts, a guard device to extend downward from the head, a frusto-conical insulating member in the guard device, the body of which is separated therefrom and is provided with a head to be supported by the guard device, a whorl of coiled conducting material fitted around said body, the second head having contacts electrically connected with the ends of said whorl, the guard device having an opening in it for the passage of radiant heat from the heating element, and the implement having means to positively separate the heating element from the part on which the implement rests.

7. An implement of the class described comprising a hollow head, a terminal member mounted in the head and provided with contacts, a guard device to extend downward from the head, a frusto-conical insulating member in the guard device and provided with a head to be supported by the guard device, a whorl of coiled conducting material fitted around the body, the second head having contacts electrically connected with the ends of said whorl, a guard device having an opening in it for the passage of radiant heat from the rheostat and the first

mentioned head having legs to rest on the support and to positively separate the heating element from the support. 30

8. An implement of the class described comprising a hollow head, a terminal mounted in the head and provided with contacts, a hollow guard device provided with a lower frusto-conical portion, the head having an opening, having pendant legs, screws tapped through the legs, the guard having a wedge surface to be engaged by the inner ends of the screws whereby when the screws are run in, the guard device will be elevated, a frusto-conical insulating member set in the guard device, spaced therefrom and provided with a head, the guard device having in its upper side a channel in which the head of said insulating body fits, a whorl or coiled conducting material fitted around the frusto-conical body, the latter having a coiled groove to receive the whorl, and contacts on the second head connected with the terminals of the whorl. 40 45 50

In testimony whereof I affix my signature.
EDWIN W. PUTNAM.
